UNITED STATES PATENT OFFICE

2,632,916

COUNTERBALANCING MEANS FOR PIVOTED
MOTOR SUCTION CLEANERSWarren A. Humphrey, Canton, Ohio, assignor to
The Hoover Company, North Canton, Ohio, a
corporation of Ohio

Application May 20, 1950, Serial No. 163,206

11 Claims. (Cl. 15—350)

1

This invention relates to suction cleaners and more particularly to the type in which the motor-fan unit is rotatably or pivotally mounted on the main chassis or frame on a transverse horizontal axis such as disclosed and claimed in the United States patent to Burkhardt 2,225,621 dated December 24, 1940.

In machines of the above type the handle and exhaust passage are rigid with the motor-fan casing. The upper end of the filter bag is carried by the handle and is detachably secured to the exhaust passage at its lower end. According to the present invention the weight of the handle and filter bag is counterbalanced by the weight of the motor. The motor-fan casing is pivoted on the motor shaft axis and a horseshoe type unicoil motor is provided in which the field of the motor is extended forwardly from the motor shaft axis. When the handle is in its operating position the weight of the motor field counterbalances the weight of the handle and bag when the cleaner is in use and holds the handle in its vertical storage position when placed in that position.

That arrangement also permits the field structure to occupy a position in the main frame not otherwise occupied and facilitates the provision of air circulating means for the ventilation of the motor. The motor extends forwardly beneath a hood on top of the main frame into a space otherwise unoccupied and has ventilating air inlet openings beneath the hood so that air is drawn inwardly from beneath the hood, flows through the motor and is discharged downwardly and rearwardly from the motor casing. That arrangement permits the ventilating openings to be hidden from view even though the ventilating structure must of necessity move with the motor casing in its pivotal movement.

Other objects and advantages of this invention will become apparent as the description proceeds when taken in connection with the accompanying drawings in which:

Figure 1 is a perspective view of the cleaner of this invention with certain parts broken away to show how the motor is arranged to counterbalance the handle;

Figure 2 is an end view of the motor fan housing of Fig. 1 taken on line 2—2 of Fig. 3 and with portions of the casing broken away;

Figure 3 is a cross-sectional view of the motor taken on line 3—3 of Fig. 2 and looking in the direction of the arrows; and

Figure 4 is a cross-sectional view through the motor taken on line 4—4 of Fig. 2 and looking in the direction of the arrows.

2

Referring to the drawings and particularly to Fig. 1 the cleaner of this invention comprises a main frame or chassis 10 mounted for ambulatory movement on front and rear wheels 11 and 12 respectively, and is provided with a downwardly facing nozzle 13 with the bumper guard 14 extending about its front end.

The main frame 10 differs from that of the above mentioned patent to Burkhardt in that it has a single passage extending from the pivotal axis of the motor-fan unit, which passage forms both the suction passage and the belt tunnel as will appear hereinafter.

The main frame 10 is provided with the suction passage 13' extending upwardly and rearwardly from the nozzle 13 to the fan eye 15. A pulley 16 forming an extension of the motor fan shaft extends through the fan eye 15 into the suction passage 13' as shown in Fig. 3. An agitator 15' is rotatably mounted in the nozzle 13 and driven by a belt 16' extending upwardly and rearwardly through the suction passage 13' and encircles the pulley 16 in a manner well known in the art. The motor fan casing 18 is pivoted to the main frame 10 by trunnion bearings 19 and 20 (Fig. 3). The trunnion bearing 19 is in the form of a sleeve 21 welded or otherwise secured to a cylindrical portion 22 of the motor housing 23. The sleeve 21 surrounds a smaller sleeve 24 secured to a bracket 25 supported from the main frame 10. The trunnion bearing 20 is in the form of a ring 26 extending from the casing 18 which encircles a smaller ring on the main frame forming the fan eye 15 which extends through the inner wall of the suction passageway similar to the construction shown in Fig. 3 of the patent to Burkhardt above mentioned. A leaf spring 27 is provided to take up any end play in the trunnion bearings.

Housed within the motor housing 23 and partially within the casing 18 is the motor proper comprising field laminations 30, a single field coil 31 and a rotor 32 mounted for rotation on suitable bearings on an axis coincident with the axis of trunnions 19 and 20. The laminations 30 are positioned within the housing 23 by cooperating lugs 28, 29, 28' and 29' concentric with the motor shaft axis so that the cylindrical portion 30' of the legs of the laminations 30 partially encircle the rotor 32 and are concentric therewith when assembled.

Rigid with the casing 18 is a handle socket 33 and an exhaust nozzle 34 detachably receiving the lower open end of a filter bag 35, the closed upper end of which is supported by the handle 36. In Fig. 1 the handle 36 is shown in its nor-

mal operating position and it is to be noted that the heaviest part of the field laminations 30 and the coil 31 extend directly forwardly from the axis of the trunnions 19 and 20 so that the weight of the handle 36 and the bag 35 is counterbalanced by the weight of the field laminations and the coil 31.

During operation of the cleaner, the handle 36 is moved upwardly and downwardly from the position shown in Fig. 1 through an operating range of movement. The normal operating range of movement of a suction cleaner handle takes place between a position substantially 30° below the vertical position to a position in which the handle extends backwardly substantially horizontally.

Mounted on top of the main frame 10 is an appearance hood 40, the forward portion of which is provided with a light transmitting lens 41 behind which a light may be mounted for illuminating the surface in front of the cleaner. A furniture guard 40' of rubber or other suitable plastic material extends over the forward portion of the hood 40 rearwardly of the nozzle 13.

The motor housing 23 extends outwardly from the casing 18 into a space in the main frame 10 beneath the hood 40 and is provided with a ventilating air inlet opening 50 (Figs. 2 and 3). The inlet 50 communicates with a passage 51 (Fig. 4) extending downwardly about the coil 31. From the passage 51 the cooling air passes between the armature 32 and the surface 30' of laminations 30, past the commutator 52, through a central opening 53 in the brush holder 54, through the motor cooling fan 55 and is discharged downwardly and rearwardly from the motor housing 23 through louvers 56.

It is to be noted that casing 18 may be made of aluminum so that the iron laminations 30 and the copper of the coil 31 form the major portion of the weight of the pivoted structure. The rotor 32, the fan and the casing 18 being generally symmetrical the positioning of the laminations and coil forwardly, throws the center of gravity of the pivoted structure well forward of its pivotal axis. When the handle 36 is in a vertical position the center of gravity of the pivoted structure will be below and forward of the pivotal axis thereof so as to hold the handle in its vertical storage position against a suitable stop which may be provided for that purpose.

The positioning of the major portion of the field laminations 30 and the field coil 31 forwardly in addition to counterbalancing the handle when the cleaner is in use and holding it in a vertical storage position when the cleaner is not in use also renders it possible to position the end of the casing in which the motor is positioned beneath the hood 40 so that all of the ventilating duct openings are hidden from view. As will be obvious in a suction cleaner of the pivoted motor fan type the ventilating system of the motor must form a part of the pivoted structure and the positioning of the motor as above described contributes to that end.

While I have shown but a single embodiment of my invention it is to be understood that that embodiment is to be taken as illustrative only and not in a limiting sense. I do not wish to be limited to the particular structure shown and described but to include all equivalent variations thereof except as limited by the scope of the claims.

I claim:

1. A suction cleaner comprising, a main chas-

sis including a nozzle mounted for ambulatory movement, a motor-fan unit including a casing pivoted to said chassis on a transverse horizontal axis, a handle and exhaust nozzle rigid with said casing, a filter bag having an open lower end secured to said exhaust nozzle and its closed upper end supported from said handle, the arrangement being such that said handle has a normal operating range inclined upwardly and rearwardly from said casing from an angle of approximately 30° from the vertical to an angle approaching the horizontal and a motor positioned in said casing in such manner as to position the major portion of the weight of the entire pivotal structure forwardly of the pivotal axis of said casing throughout the entire range of movement of said handle in its inclined operating range whereby to counterbalance the weight of said handle and filter bag.

2. A suction cleaner according to claim 1 in which said motor includes a rotor rotatably mounted on the pivotal axis of said casing, U-shaped laminations the legs of which substantially embrace said rotor with the closed end thereof extending forwardly of the pivotal axis of said casing when said handle is in its operating range and a field coil surrounding the closed end of said laminations.

3. A suction cleaner according to claim 2 in which said casing is formed with a motor ventilating passage including an air inlet positioned above the pivotal axis of said casing when said handle is positioned in its operating range, an air duct leading from said inlet forwardly and downwardly about the closed end of said laminations and about said field coil, laterally between said rotor and the legs of said laminations and downwardly and rearwardly to an air exit formed in the bottom rear portion of said casing.

4. A suction cleaner according to claim 1 in which said motor is of the unicoil type having a rotor rotatably mounted on the pivotal axis of said casing, field laminations extending forwardly from said rotor and a field coil surrounding the forwardly extending portion of said laminations.

5. A suction cleaner according to claim 4 in which said casing is provided with a ventilating duct leading forwardly and downwardly about the forwardly extending portion of said laminations and about said field coil, laterally between said rotor and laminations and downwardly and rearwardly to an outlet in the bottom rear portion of said casing.

6. A suction cleaner comprising, a main body including a nozzle mounted for ambulatory movement, a casing pivotally mounted on said body on a transverse longitudinal axis, a motor-fan unit in said casing, and a handle rigid with said casing and extending upwardly and rearwardly when in its operating range from an angle acute to the vertical to an angle approaching the horizontal, the motor of said motor-fan unit being of the unicoil type having field laminations extending forwardly from the pivotal axis of said casing so as to position the center of gravity of the entire pivotal structure forwardly of the pivotal axis thereof throughout the entire operating range of said handle.

7. A suction cleaner according to claim 6 in which said field laminations and coil are positioned below and forwardly of the pivotal axis of said casing when said handle is in a vertical position so as to hold said handle in that position.

8. A suction cleaner comprising, a main body including a nozzle mounted for ambulatory movement, an appearance hood forming the top of said body, a pivoted structure including a casing pivotally mounted on said body on a transverse horizontal axis and having one end thereof positioned beneath said hood, a handle rigid with said casing, said handle being movable from a substantially vertical position to a position approaching the horizontal, a motor-fan unit within said casing, said unit including a motor positioned in the end of said casing beneath said hood having a rotor rotatably mounted on the pivotal axis of said casing, field laminations and a field coil with the major portion of said laminations and said coil positioned forwardly of said axis so as to position the center of gravity of said pivoted structure forwardly of said axis throughout the entire range of movement of said handle and a ventilating duct leading from beneath said hood over said laminations, coil and rotor and exhausting through an outlet in the rear bottom portion of said casing.

9. A suction cleaner comprising, a main body including a nozzle mounted for ambulatory movement, a pivotal structure including a motor-fan unit having a casing pivoted to said body on a transverse horizontal axis toward the rear of the body and a handle rigidly secured to said casing and extending upwardly and rearwardly from an acute angle to the vertical to an angle approaching the horizontal when in its operating range and being movable to a vertical storage position, said motor-fan unit being so positioned in said casing that the center of gravity 35 of said structure is forward of the pivotal axis of said casing when said handle is in its opera-

25

20

tive range and below said axis when said handle is in a vertical position.

10. A suction cleaner comprising, a main body including a nozzle mounted for ambulatory movement, a pivotal structure, said structure including a motor fan unit having a casing mounted on said body for pivotal movement on a transverse horizontal axis and a propelling handle rigid with said casing, said handle being movable from a vertical storage position to a position approaching the horizontal, said motor-fan unit including a motor of the unicoil type having the coil thereof positioned forwardly of said axis in a position to locate the center of gravity of said pivoted structure forwardly of said axis throughout the entire range of movement of said handle.

11. A suction cleaner according to claim 10 in which the location of said coil is such that the center of gravity of said pivoted structure is below said axis when said handle is in its vertical storage position.
